SPRAYER CONSTRUCTION

Nicholas W. De Frees, Hastings, Minn., assignor
to H. D. Hudson Manufacturing Company,
Chicago, Ill., a Corporation of Minnesota

Application February 18, 1931. Serial No. 516,676

9 Claims. (Cl. 221—77)

This invention relates to improvements in sprayers of the type in which a pump unit is removably mounted in a tank, with the piston or pump rod extending outwardly from the end 5 of the cylinder and tank, and having a grip thereon for operating it. In devices of this kind, the pump rod grip and the pump rod serve as means for carrying the tank.

In this art, it has long been the practice to 10 provide a tank and cylinder capping elements co-operating with means attached to the tank wall, for clamping the cylinder, in sealed relation to an opening in the tank wall. It has, moreover, been the practice to threadingly connect 15 the cap to a tubular extension of the tank wall, but this latter practice involves considerable expense, not allowable in a highly competitive market. It has also been the practice to rivet an annulus to the outer side of the top wall of the 20 tank and to provide the annulus with inclined surfaces simulating a single thread, with which surfaces corresponding surfaces of the cap engage, so that when the cap is rotated a wedging 25 action results, whereby, due to reaction between annulus and tank wall, the cap is pressed against the cylinder, causing said cylinder to sealingly close the tank opening, so that fluid leakage is 30 prevented during pumping action. This old practice puts considerable strain on the tank wall, tending to loosen the rivets, and makes it difficult 35 to maintain pressure in the tank because of leakage. The annulus is formed of sheet metal, and this is a cheap construction, but, due to force reactions above mentioned, is also ob- 40 jectionable. It is, therefore, an object of this invention to provide a device of the nature mentioned in which there is no wedging reaction between the tank wall and the ring, and, therefore, no loosening of rivets and leakage, due to 45 this strain. This is accomplished herein by having the cylinder directly supported by the ring, instead of by the tank wall. In this way, the wedging reaction is taken entirely by the ring, and not at all by the tank.

Features include: the supporting of the cylinder, cap, and wedging means directly by an annulus which is formed from one piece of metal; the specific construction of the annulus, the formation of a bead on the rim of the cylinder 50 which engages a gasket in a manner to squeeze it in directions axially of the tank and cylinder, as well as radially inwardly toward the cylinder wall; to provide circumferential stiffening portions on the ring, between the wedging surfaces; 55 and to provide an annular depression in the ring which acts both to set the gasket, and to center the ring in the tank opening.

Objects, features, and advantages of the invention will be set forth in the description of the drawing forming a part of this application, and 60 in said drawing.

Figure 1 is a vertical section through the top 65 of a tank having a cylinder and piston therein, and showing one embodiment of my invention;

Figure 2 is a side view of the structure of Figure 1, showing the cap disengaged, and the piston partly withdrawn, with the cap positioned so that after downward motion and engagement with the annulus, it is positioned to be clampingly 70 engaged by a rotative motion; and

Figure 3 is a plan section on line 3—3 of Figure 1, showing the cap in operative clamping position.

Numerical 1 indicates the tank having an upper outwardly curved wall 2, said wall having an 75 opening 3 therein. The annulus generally indicated at 5 is very cheaply formed from a single piece of sheet metal and is provided with a depressed central portion 6 forming a shoulder 7 which engages snugly in the opening 3 centering 80 the annulus, and also forming a depression 8 extending downwardly from its upper side to receive a gasket 9. The depressed portion 6 has an opening 10 and through this opening the cylinder 11 passes downwardly into the tank. 85 The cylinder has a cross-sectionally arcuate circumferential rim bead 15, engaging the top of the gasket as shown. This is a feature. It will be noted that the lower surface of this bead is concave and that when pressure is applied to 90 the bead by the cap, the gasket material is forced downwardly and pulled inwardly and jammed against the outer periphery of the cylinder and positioned to seal the cylinder-receiving opening 10 of the annulus. The depressed portion 95 6 acts as a centering element for the annulus, and rivets 16 pass through the outer lower wall portion 17 and through the wall 2. The annulus has an upstanding wall stiffening portion 18. The wall is formed to provide circumferentially 100 spaced elements, three in number, and the tops of these elements are turned over as at 20 to form helices or cam surfaces, the surfaces being spaced from one another and being slanted downwardly in clockwise direction, as the threads 105 of a right-hand screw. Between the thread-forming flanges 20, the upstanding wall portion 18 is cut slightly away as shown but is so cut as to leave reinforcing or stiffening portions 23 110 between each flange 20, which portions are, of

course, continuous with the wall 18. This is also a feature of the invention which makes the annulus much more resistant to deformation, which might result from the wedging action of the elements.

5 The cap in this instance is in the form of a casting, and provides three projecting portions 25, which are of less circumferential extent than the corresponding spaces between the flange-carrying elements, so that these projections may be moved into these spaces from the position shown in Figure 2. The portions 25 are relatively helically arranged and also slant downwardly in clockwise direction, and when the cap has been moved to bring the portion 25 below the flanges 20, and on rotation to the right, these elements 25 assume wedging relation with the inclined flange portions 20, as shown in Figures 1 and 3, and pressure is applied to beaded rim 15, and the gasket sealingly compressed, as shown.

10 The provision of a continuous wall 18 is a feature of the invention, and it will be noted that the upper edge of the portions 23 of the wall are substantially flush with the under side of the cam surfaces 20. This continuous upstanding wall 18 facilitates the filling of the tank, serving the part of a funnel. This enables the cam surfaces to be properly shaped without the use of a support at the inside surfaces, which use would necessarily greatly increase the cost of production. The arrangement also permits a shorter length of cam surface projection, greatly adding to the strength, and decreasing the probability of the metal drawing out of shape during the forming operation.

15 The top of the cap is provided with a hollow wrench projection 30 by which the cap can be rotated to perform its wedging action. The cap has an opening 31, through which the pump or cylinder rod 32 passes. The extension 30 has at its top a central opening 33, and diametrically arranged recesses 35 extending outwardly from and intersecting the opening 33, and the nut also provides shoulders 36-37 lying outwardly beyond and intersecting the opening. The pump rod has a handle as an extension of a cylindrical portion 39, in threaded connection with rod 32. This cylindrical portion has lugs 38 diametrically arranged and adapted to enter the recesses 35, as shown in Figure 3, and to engage the shoulders 36-37 when rotated in counter-clockwise direction. When the lugs are engaged with the shoulders and when the pump rod is slightly withdrawn, the lugs 38 move upwardly into diametrically arranged pockets 40 in the manner shown in dotted lines in Figure 2 so that the tank, now connected with the cap through the threads, cannot rotate to bring the lugs into registration with recesses 35, as shown in Figure 3, which would result in the tank dropping downwardly.

20 Another feature of the invention relates to the arrangement of the helix-forming segments, and the relation of the bend-lines of these segmental portions to the upper un-bent edges of the intervening portions of the upright wall of the cup-like annulus. The bend lines of the segmental flanges slant generally in the same direction at angles to a horizontal plane. The upper edges of the un-bent intervening wall portions 23 are slanted in a direction opposite to that of the bend lines of the helix-forming flanges, and it will be noted that the ends of the bend lines of the flanges substantially intersect or are coincident or at the same level or in the same plane with

25 the corresponding ends of these edges. The upper edge, including the helix-forming portions, is, before the bending operation, so arranged that the line of bend is determined by the junction points. In the drawing, the junction points have been indicated by the numerals 20^a-20^b and the upper edge has been indicated by the numeral 20^c. The bend line is indicated 20^d. This is a valuable feature of the invention. The ends of the bend lines intersect the ends of the top edges 20^c at points 20^a-20^b. In this way, the portions 23 reinforce the helix-forming sections or flanges 20 at the bend or helix line, during and after bending. A forming die applies pressure to the upstanding sections 20, and moves the sections 30 downwardly and inwardly along the bend line established or defined between points 20^a-20^b. In any different structure, as where the top edges of the inter-helix stiffening wall portions 23, do not intersect at points which correspond to the ends of the helix bend line, the proper points of support are not established, so that die-forming cannot be accomplished without arranging a matrix within the annulus during forming. When a matrix having surfaces corresponding or coincident with the helix bend line are used, it is necessary to thereafter remove the matrix, which is a troublesome and time-consuming operation. The present invention, therefore, provides a structure which can be properly formed, without the use of an internal core of matrix die, thus materially reducing production costs.

35 I claim as my invention:

1. A device of the class described comprising a tank, having an opening, an annulus having a wall engaging the tank wall and overlying the opening, that part of the annulus wall which overlies the tank opening having an opening, a gasket surrounding the annulus opening, a cylinder passing through the gasket and annulus opening and having a flange engaging the gasket, a piston rod for the cylinder, a cap traversed by the piston rod, said annulus and cap having means cooperable to cause said cap to press the flange against the gasket when the cap is rotated, means by which rotation of the rod rotates the cap, and means sealingly securing the tank wall-engaging portion of said annulus wall to said tank wall.

2. A device of the class described comprising a tank having an opening, an annulus engaging the top surface of the top of the tank and having a pressed-out portion which enters the opening to center the annulus, said pressed-out portion having an opening, a gasket supported by the pressed-out portion and surrounding the annulus opening, a cylinder having a marginal flange engaging the gasket, a piston rod for the cylinder, a cap traversed by the piston rod, said annulus and cap having means cooperable to cause said cap to press the flange against the gasket, and means on cap and rod cooperable to cause the cap to press the flange against the gasket.

3. A device of the class described comprising a tank having an opening in its top wall, an annulus and means securing it to the outer side of the top wall, said annulus having a wall portion overlying the top wall and opening and having an opening in that wall portion which overlies the tank opening, a gasket engaging the annulus and surrounding the annulus opening, a cylinder extending through gasket and annulus opening, and having a bead engaging the gasket, a piston rod for the cylinder, a cap traversed by the piston

rod, said annulus and cap having helical means wedgingly cooperable to cause the cap to press the bead against the gasket when the cap is rotated, whereby the wedging strains are taken only by 5 the annulus member and none transmitted to the tank wall, and means on the cap and rod cooperable to cause the cap to press the bead against the gasket.

4. A device of the class described comprising 10 a tank having an opening, an annulus having a wall engaging the tank wall and overlying the opening, said annulus having a pressed-out portion which enters the opening to center the annulus and to provide a depression at the outer 15 side of the annulus, said pressed-out portion having an opening, a gasket supported by the pressed-out portion and surrounding the annulus opening, a cylinder passing through the gasket and annulus opening, and having a flange engaging 20 the gasket, a piston rod for the cylinder, a cap traversed by the piston rod, said annulus and cap having means cooperable to cause said cap to press the flange against the gasket, means on cap and rod cooperable to cause the cap to press the 25 flange against the gasket and means securing said annulus to said tank wall.

5. A device of the class described comprising 30 a tank having an opening, an annular single-piece cup-like stamped metal member having a bottom wall and a circumferentially continuous side wall and adapted to act as a filling funnel for the tank and secured to the outer surface of the tank about the opening, a gasket supported by the bottom wall of the member, a cylinder passing 35 through the gasket, bottom wall of the member, and through the tank opening, and having a flange engaging the gasket, a piston rod for the cylinder, a cap traversed by the piston rod, the rim of the circumferential continuous side wall 40 of the member having inwardly-bent, horizontally-disposed spaced helix-forming flanges, said cap having means cooperable with said flanges to press the cylinder flange against the gasket when the cap is rotated, and means on the cap and 45 rod cooperable to cause the cap to press the flange against the gasket.

6. A device of the class described comprising a 50 tank having an opening, a cup-like annulus having a bottom wall the outer portion of which sealingly engages the outer surface of a tank wall, said bottom wall having a shallow centrally depressed portion forming a sealing shoulder fitting the opening of the tank, the depressed portion having therein an opening of less area than the depressed portion, the upstanding circum- 55 scribing wall portion of said cup-like annulus having at its upper edge a series of in-turned bent-over segmental portions overlying the bottom wall of the annulus but not overlying the opening of the depression, the lower surfaces of the segmental portions and the bend lines being slanted in one direction to cooperate to form a helix, the upper edges of the un-bent intervening wall portions being slanted in an opposite direction, and the ends of the bend lines at the 60 junction points with said slanted edges being substantially in the same plane with the ends of said edges, a gasket supported by the depressed portion and circumscribing the opening of said depressed portion, a cylinder passing through the gasket and annulus opening and having a flange 65 engaging the gasket, a piston rod for the cylinder, 70

a cap traversed by the piston rod, said cap having means cooperable with said segmental portions to cause the cap to press the flange against the gasket when the cap is rotated and means by which rotation of the rod rotates the cap.

7. A device of the class described comprising a 75 tank having a top wall having an opening therein, an annular element circumscribing the opening and having a bottom wall which circumscribes the opening and sealingly engages the top surface of the top wall of the tank at a point outwardly beyond the opening, said bottom wall having a shallow depressed wall portion within and cooperating with the opening to form a seal and acting as a centering and gasket-pocketing 80 means, a gasket in said pocket, said depressed wall portion having an opening which the gasket circumscribes, a cylinder traversing the last mentioned opening and having a flange which engages over the washer, a cap and means carried by the annulus and cap cooperative on rotation of the cap to press the cylinder flange against the gasket, a piston rod for the cylinder and means on cap and rod cooperative to rotate the cap to cause it to press the cylinder flange against 85 the gasket.

8. A device of the class described comprising a 90 tank having an opening, a cup-like annulus having a bottom wall having an opening therein, said annulus having an upstanding cylindrical wall 95 having at its upper edge a series of segmental in-turned bent-over portions overlying the bottom but not overlying the opening, the lower surfaces of the segmental portions and the bend lines being slanted to cooperate to form a helix, the 100 ends of the upper edges of the un-bent intervening upstanding wall portions and ends of the bend lines of the segmental portion being substantially in the same plane at the junction points, the bottom wall of said annulus being engaged with 105 the tank wall and having a portion overlying the tank opening, a gasket surrounding the annulus opening, a cylinder passing through the gasket and annulus opening and having a flange engaging the gasket, a piston rod for the cylinder, a 110 cap traversed by the piston rod, said cap having means cooperable with the segmental portions to cause the cap to press the flange against the gasket when the cap is rotated and means on cap and rod cooperative to cause the cap to press the 115 flange against the gasket.

9. A device of the class described comprising a 120 tank having a top wall having an opening therein, an annular element of sheet metal circumscribing the opening and having a bottom wall 125 which sealingly engages the top surface of the top wall of the tank at a point outwardly beyond the opening, said bottom wall having a shallow depressed portion within and cooperating with the edges of the opening to form an additional 130 seal and acting as a centering and gasket-pocketing means, a gasket in said depressed wall portion, said portion having an opening which the gasket circumscribes, a cylinder traversing the last mentioned opening and having a flange which engages over the gasket, a cap, means carried by the annulus and cap cooperative on rotation of the cap to press the cylinder flange against the gasket, a piston for the cylinder having a rod 135 traversing the cap and means carried by the cap and rod for rotating the cap by the piston.

NICHOLAS W. DE FREES.
